TEAR GAS WEAPON

William H. Hiser, Decatur, Ill., assignor to
Kenneth W. Connor, St. Louis, Mo.

Filed Jan. 25, 1965, Ser. No. 83,570

Term of patent 14 years

(Cl. D30—1)

FIG. 4

FIG. 2

FIG. 1

FIG. 3

FIG. 5

FIG. 6

FIGURE 1 is a front elevational view of a tear gas weapon showing my new design.

FIGURE 2 is a side elevational view taken from the left hand side of FIGURE 1.

FIGURE 3 is a side elevational view taken from the right hand side of FIGURE 1.

FIGURE 4 is a top plan view thereof.

FIGURE 5 is a rear elevational view thereof.

FIGURE 6 is a bottom plan view thereof.

I claim:

The ornamental design for a tear gas weapon, substantially as shown.
